FUEL BURNING APPARATUS

Lanson B. Joyner, Pasadena, Calif., assignor of
one-half to Schuyler C. Joyner, Pasadena,
Calif.

Application May 29, 1933, Serial No. 673,508

2 Claims. (Cl. 122—32)

This invention relates to liquid fuel burning apparatus, and same has for its primary object the provision of means whereby liquid hydrocarbon can be maintained at an effective vaporizing temperature and supplied to a liquid fuel burner to more readily insure combustion of the fuel and a free uninterrupted flow of the fuel to the burner without carbonization thereof and in a manner that will permit low grade fuel to be employed in an efficient and highly economical manner.

The invention is particularly designed for use in connection with boilers of the so called "locomotive portable type" wherein a cylindrical shell or barrel extends horizontally from the fire box to the front part or smoke box end of the boiler, and wherein the fire box is connected to the smoke box by a number of tubes, through which the products of combustion pass on their way to the chimney. In boilers of this type the fire box is partly defined by spaced apart vertical, hollow water legs, which extend longitudinally from the front of the shell and vertically from the sides of the shell to the base of the structure or to the bottom of the fire box. My invention is designed whereby the water space in one of the aforementioned vertical water legs is adapted to be employed to accommodate a preheating circulating coil which will be constantly submerged in the water contained in said leg and effectively subjected to the temperature of said water, whereby as heavy liquid hydrocarbon is passed through the coil, it will be heated to such extent that it will readily vaporize at the orifice of a liquid fuel burner. I find that the temperature of the water at one place in the hollow water leg is almost uniformly maintained at a temperature of approximately 180° F. and that this temperature to which the coil is subjected is decidedly effective for the purpose of breaking down the viscosity of heavy, low grade hydrocarbon fuel and to the end that much economy can be effected in the operation of boilers of the type herein referred to.

An essential object of the invention resides in the provision of means in the form of an attachment to such boilers that may be quickly applied to the vertical water leg without requiring costly alterations to be made in the construction thereof and which may be applied with like convenience to any common form of liquid fuel burner.

Another object of the invention is to provide preheating means for liquid hydrocarbon which, when extended into the water leg of the boiler, will be protected by the water against premature

destruction, such as would happen were the device permitted to directly contact with a flame.

A still further object of the invention is to provide preheating means for liquid hydrocarbon which will function in a reliable manner to prevent carbonization of the fuel at any place in the system between the coil employed and the orifice of a fuel burner with which device it is designed to be used.

Other important objects of the invention will be readily apparent and more fully pointed out from the following description and particularly pointed out in the accompanying drawings, in which

Figure 1 is a sectional perspective view of the device when applied to a boiler and connected with a liquid fuel burner;

Figure 2 is a vertical longitudinal section through the device;

Figure 3 is a view in front elevation of the device; and

Figure 4 is a view in rear elevation of the device.

I have described the type of boiler with which the invention is designed primarily to be used and it is believed that it is sufficient to say that the boiler herein illustrated comprises a horizontal, cylindrical shell or barrel 5 of which the hollow, vertically spaced apart water legs 6 form a part thereof. Each of said legs has its spaced apart walls connected together by the customary transverse stay bolts 3. The legs extend in a downward direction from the sides of the shell 5 and same are connected with the fire box wall 6a of the boiler structure, in which said wall is the customary opening 7 through the fire doors 8 of which is extended the nozzle 9 of a liquid fuel burner 10, by means of which a flame is adapted to be projected into said fire box as is also common in the art.

My preheating device 11 comprises a set of 40 identical circulating tubes 12 disposed preferably in relative parallelism and whose front ends connect with a header 13 and whose rear ends connect with a header 14. Any desired number of the tubes 12 may of course be employed but I 45 have found four thereof to be entirely suitable for my purpose. The header 14 is divided internally by a partition 15 to provide non-communicating spaces 16 and 17 and the header 13 is divided by partitions 18 and 19 to provide substantially similar upper and lower spaces 20 and 21 and an intermediate and somewhat larger space 22. The lower tube 12 of the set employed extends from the space 20 of the header 13 to the space 16 of the header 14 and the tube 12 50

immediately thereabove passes from the said space 16 in the header 14 to the space 22 in the header 13. The lower one of the two upper tubes extends from said space 17 to the space 22 and 5 the extreme upper tube extends from the space 21 to the aforementioned space 17. It is in this manner that a sinuous course or lane is provided over which liquid hydrocarbon from a supply source is adapted to flow and to finally pass from 10 a discharge pipe 23 to said burner nozzle 9.

The header 13 is securely bolted to the front wall of the boiler structure, as shown at 24, and same serves to effectively seal an opening 25 which I cause to be formed in said front wall so 15 that all of the tubes 12 will project into the water leg at the right of the structure as shown in Figure 1 of the drawings. It will be noted that the opening 25 is positioned with respect to the stay bolts 3 so that the weight of the tubes will be 20 sustained by said bolts. It obviously follows that when mounted as first stated, my preheating device will be entirely submerged in the water contained in said leg 6. In this manner the device is protected against the injurious effect of a direct 25 flame and it follows also that the heat of the water in said leg 6, which generally is about 180° F., when the boiler is in operation, will be entirely sufficient to maintain the tubes 12 at a temperature that will serve to break down the viscosity 30 of the liquid fuel when the device is in operation and thereby condition the fuel for effective vaporization thereof at the burner orifice.

The front wall of the header 13 and the rear wall of the header 14 are formed with relatively 35 alined threaded passages 26 and same are alined with the adjacent tubes 12, whereby to permit a cleaning tool (not shown) to be passed through said tubes whenever desired. Said passages 26 are normally closed by removable plugs 27.

40 An intake pipe 28 leads to the space 20 and the fuel as it enters said space proceeds through the pipes 12, as shown by the arrows in Figure 2. From the space 21 the fuel in a heated state is conducted through said pipe 23 for discharge at 45 said burner 10. The pipe 23 has a vertical branch 29 around which is an electrically heated coil 30 adapted to be supplied with current in any suitable well known manner. Fuel may be passed around the header 13 so as to not enter the pipes 50 12 and to accomplish this I employ a by-pass valve 31. This I would use when the boiler has been shut down for an appreciable period of time and is cold. It follows that when oil is by-passed around the header 13, it will be subjected to the 55 effect of heat produced at said coil 30. A thermometer 32 at the pipe 23 serves to indicate the temperature of the fuel when heated by the coil 30 and a similar thermometer 32^a at the header 13 serves to indicate the temperature of the fuel 60 as it leaves the space 21. After the boiler has been fired and the temperature of the water in the leg 6 has reached 180° F. or thereabout, the fuel coil 30 is thrown out of operation and the fuel valve 31 closed so as to cause the fuel from the 65 source of supply to enter said pipes 12 as afore-stated. The lower end of the pipe 23 is formed

into an angular branch 23^a having a control valve 33 for regulating the admission of the fuel to a flexible tube 34, the latter having one of its ends attached to the burner nozzle 9.

5 From the construction of the device as herein set forth, it is manifest that same may be quickly installed upon a boiler structure without requiring expensive alterations to be made in the construction thereof, it being required simply that an opening 25 be formed in the front wall of the boiler in line with the aforementioned leg 6, and that the device be passed through said opening to dispose same directly above the stay bolts 3. When this is accomplished, the header 13 10 serves to securely close said opening and the device is now ready for use in the manner and for the purpose stated.

15 I claim:

1. The combination, with a boiler structure having a longitudinally extending water leg at 20 one side and a horizontal series of tie rods located in said water leg and extending from one side wall thereof to the other, the said boiler structure having its front wall formed with an opening, the bottom of which is substantially 25 alined with said series of tie rods, of a liquid fuel pre-heating organization including inner and outer headers and fuel circulating tubes connecting the headers with each other and co-operable therewith and with each other to cause 30 fuel when delivered to the outer header to be conducted to the inner header, thence back to the outer header by means of the respective tubes, the inner header being of a size for free passage 35 through the aforesaid opening and adapted to be extended into said water leg and to rest upon said tie rods, the outer header being firmly secured to the front wall of the boiler in a position to wholly cover and seal said opening; and a discharge pipe leading away from the outer header 40 and provided with valved means adapted to be connected with a liquid fuel burner, as and for the purpose set forth.

2. The combination with a boiler structure 45 having a longitudinally extending water leg including spaced parallel side sheets at one side and said structure having its front wall provided with an opening which communicates with said water leg; of a liquid fuel preheating organization including inner and outer headers and fuel 50 circulating tubes connecting the headers with each other and being co-operable therewith and with each other to enable fuel when delivered to the outer header to be conducted to the inner header, thence back to the outer header by means of said 55 tubes, the inner header being of a size to freely enter the opening in the front wall of said structure, the outer header being removably secured to said front wall and disposed to wholly cover said opening and seal same; a discharge pipe leading from the outer header and provided with valved means 60 adapted to be connected with a liquid fuel burner, and means for simultaneously maintaining the spacing of the sheets and supporting said pre-heating organization.

65 LANSON B. JOYNER.
